(57) **CLAIM**

The ornamental design for the display screen with animated graphical user interface, as shown and described.

DESCRIPTION

FIG. 1 is a front view of a first image in a first embodiment of a sequence of a display screen with an animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is a front view of a fourteenth image thereof;

FIG. 15 is a front view of a fifteenth image thereof;

FIG. 16 is a front view of a sixteenth image thereof;

FIG. 17 is a front view of a seventeenth image thereof;

FIG. 18 is a front view of a first image in a sequence of a second embodiment display screen with an animated graphical user interface showing our new design;

FIG. 19 is a front view of a second image thereof;

FIG. 20 is a front view of a third image thereof;

FIG. 21 is a front view of a fourth image thereof;

FIG. 22 is a front view of a fifth image thereof;

FIG. 23 is a front view of a sixth image thereof;

FIG. 24 is a front view of a seventh image thereof;

FIG. 25 is a front view of an eighth image thereof;

FIG. 26 is a front view of a ninth image thereof;

FIG. 27 is a front view of a tenth image thereof;

FIG. 28 is a front view of an eleventh image thereof;

FIG. 29 is a front view of a twelfth image thereof;

FIG. 30 is a front view of a thirteenth image thereof;

FIG. 31 is a front view of a fourteenth image thereof;

FIG. 32 is a front view of a fifteenth image thereof;

FIG. 33 is a front view of a sixteenth image thereof; and,

FIG. 34 is a front view of a seventeenth image thereof.

(Continued)

The appearance of the transitional image sequentially transitions between the images shown in FIGS. 1 to 17 and FIGS. 18 to 34. The process or period in which an image transitions to another image forms no part of the claimed design.

The broken lines of uneven length show the display screen and form no part of the claimed design.
